INVENTOR.

George W. Lord

UNITED STATES PATENT OFFICE.

GEORGE W. LORD, OF BOSTON, MASS., ASSIGNOR TO THE LORD ACOUSTIC TELEPHONE MANUFACTURING COMPANY, OF PORTLAND, ME.

MECHANICAL TELEPHONE.

SPECIFICATION forming part of Letters Patent No. 359,215, dated March 8, 1887.

Application filed September 27, 1886. Serial No. 214,622. (No model.)

To all whom it may concern:

Be it known that I, GEORGE W. LORD, a citizen of the United States, residing at Boston, in the county of Suffolk and State of Massachusetts, have invented a new and useful Improvement in Mechanical Telephones, of which the following is a specification.

In a mechanical-telephone system it has been found that the vibrations are transmitted most successfully when the conducting-wire extends straight away from the transmitter in a direction at a right angle to the plane of the transmitting-diaphragm; but as this direction is not always practicable in the construction of lines the full efficiency of this form of telephone is not always attained. It is also desirable that the telephonic instruments should be insulated or detached as far as possible from surrounding objects.

20 The object of this invention is to obtain a mechanical telephone from which the line can always be extended for a considerable distance in a direction at right angles to the plane of the diaphragm sufficient to insure the satisfactory transmission of vibrations, no matter in what direction the line may extend from the points which are connected, thus enabling the use of the mechanical telephone to be largely increased. It also has for its object 25 the complete insulation of the telephones, and, in addition, the increased efficiency of the same.

To the end that these results may be accomplished, the invention consists in the combination of a mechanical-telephone case with 30 flexible attaching devices which allow it to be turned conveniently in any direction, as hereinafter set forth.

The invention also consists in the construction of the telephone, as hereinafter more fully set forth.

In the accompanying drawings, Figure 1 is a sectional view of my improved telephone attached to the wall of a building. Fig. 2 is a plan view of the same, and Fig. 3 is another plan view showing the line extended at an acute angle to the wall of the building.

In these several figures the same letters refer to the same parts.

Referring to the drawings, A is the conducting-wire.

B is a wall, to which the telephone is at-

tached, and C is the telephone. This consists of a hollow case, of wood, of an oval form and made in two parts, a and b. It is provided with perforations at each end.

55 D is the diaphragm, which may be made of any suitable material and is secured across the case, so that there is a cavity on each side of the diaphragm. A convenient manner of securing the diaphragm between the two parts of the case is shown in the drawings. The diaphragm D is stretched over a wooden ring, c, and suitably secured to the same. This ring rests in a recess in the section a, and bears against a shoulder on the same. The other section bears flatly against the ring. When the diaphragm has been placed in position, the two sections of the case are united together in any suitable manner. Around the outside of the case is a band, E, of some non-resonant material suitably secured to the case, the effect of which is to prevent any resonance in the case. It has been found that sheet-lead is a suitable material for this band; but any other suitable material may be used. A band or 75 lining of non-resonant material may be placed inside the case.

70 F is a wire, which is connected by a nut, d, to a knob of wood on the inside of the diaphragm and passes through the same, as in other mechanical telephones. This wire passes through a perforation in a plug of vulcanized rubber, e, which is inserted into the perforation in the section a of the case. This wire F is provided with a link, g, to which the line 85 wire is attached.

For the purpose of attaching the case in any desired position, suitable wires or cords, L, are used, which pass through and are attached to rings H on the sides of the case, said cords or 90 wires being attached to some stationary support. These flexible connections permit the telephone, when the line-wire is stretched, to be set at any desired angle to the wall of a building, as shown in Fig. 3, while at the same 95 time the conducting-wire will be maintained at right angles to the diaphragm. A tube, I, which is preferably a flexible speaking tube—such as is used with some forms of telephones—connects the interior of the section b with the 100 interior of the building.

The perforation in the section b is directly

opposite the center of the diaphragm, and consequently in connection with the hollow chamber in front of the diaphragm. The sound-waves transmitted through the tube I are received most effectively and, without loss of intensity, are concentrated upon the diaphragm.

As shown in Fig. 3, the speaking-tube I may have a branch ear-tube, k, attached to it, so that the user may speak and hear at the same time.

For the purposes of a call, an ordinary electric call-bell connected to the conducting-wire may be used, or in some cases a whistle within the speaking-tube will be sufficient.

15 This form of telephone may be placed within a building as well as outside of the same.

In my Patent No. 356,594, granted January 25, 1887, I have shown a telephone of construction similar to that herein described, and having a weight suspended from it by flexible cords. This combination I do not claim in the present application; nor do I broadly claim the combination of the flexible cords and telephone without the support.

25 Having thus described my invention, what I claim, and desire to secure by Letters Patent of the United States, is—

1. A telephone-case, in combination with the flexible cords or wires attached to each 30 side of said case and to a suitable support, substantially as set forth.

2. The elongated telephone-case C, in combination with the cords or wires attached to each side of said case, extending along the

same and attached to a support, substantially 35 as set forth.

3. The combination, substantially as and for the purpose set forth, of the case C, the diaphragm D within said case, the conducting-wire A, the flexible connections L L, attached 40 to each side of the case and each attached to the outside of a building, and a tube connecting the interior of the case to the interior of the building.

4. An oblong telephone-case consisting of 45 two wooden sections, in combination with a diaphragm held between said sections and having a cup-shaped cavity or space on each side of it, and wire connected to said diaphragm, substantially as set forth. 50

5. The combination of a telephone-case consisting of two sections with a band or envelope of non-resonant material surrounding said sections at the joint and extending along the surface of said sections, substantially as set forth. 55

6. In combination with the telephone-case, the diaphragm, and the conducting-wire, the long rubber plug e, inserted in one end of said case and surrounding said wire, substantially as set forth. 60

In witness whereof I have hereunto set my hand in the presence of the subscribing witnesses.

GEORGE W. LORD.
